(57) **CLAIM**

The ornamental design for a foldable game board as shown and described.

DESCRIPTION

FIG. 1 is a perspective view, taken from above, of a foldable game board showing my new design, in an unfolded state; FIG. 2 is a perspective view thereof, taken from below, in the unfolded state;

FIG. 3 is a top view thereof, in the unfolded state;

FIG. 4 is a bottom view thereof, in the unfolded state;

FIG. 5 is a left side view thereof, in the unfolded state;

FIG. 6 is a right side view thereof, in the unfolded state;

FIG. 7 is a front view thereof, in the unfolded state;

FIG. 8 is a rear view thereof, in the unfolded state;

FIG. 9 is a perspective view thereof, taken from above, in a first folded state;

FIG. 10 is a perspective view thereof, taken from below, in the first folded state;

FIG. 11 is a top view thereof, in the first folded state;

FIG. 12 is a bottom view thereof, in the first folded state;

FIG. 13 is a left side view thereof, in the first folded state;

FIG. 14 is a right side view thereof, in the first folded state;

FIG. 15 is a front view thereof, in the first folded state;

FIG. 16 is a rear view thereof, in the first folded state;

FIG. 17 is a perspective view thereof, taken from above, in a second folded state;

FIG. 18 is a perspective view thereof, taken from below, in the second folded state;

FIG. 19 is a top view thereof, in the second folded state;

FIG. 20 is a bottom view thereof, in the second folded state;

FIG. 21 is a left side view thereof, in the second folded state;

FIG. 22 is a right side view thereof, in the second folded state;

FIG. 23 is a front view thereof, in the second folded state; and,

FIG. 24 is a rear view thereof, in the second folded state.
